W. G. JOHNSTON.
MILL.

Patented May 3, 1832.

William G. Johnson, Philadelphia Pa.

Letters Patent.

The schedule referred to in these Letters Patent, and making part of the same, containing a description in the words of the said William Johnson himself of his improvement in mill for grinding wheat, rye, and other grain for flour, feed and other purposes, and for grinding paints, dye stuffs, plaster &c.

Be it known that I William G. Johnson of the city of Philadelphia, in the County of Philadelphia and State of Pennsylvania, have invented a new and useful improvement in mill for grinding wheat, rye, and other grain for flour, feed and other purposes; and for grinding paints, dye stuffs, plaster &c. which is described as follows

The mill and gearings, with its fixtures may be constructed in the usual, or in any other convenient manner; excepting the apparatus for holding or pressing the stones together. The improvement relates solely to the plan of holding or pressing the upper stone (when that is the moving stone) down on the other or on the substance to be ground, when the stone is made so small that its specific gravity, or weight, is insufficient for that purpose; and when the lower stone is the moving stone, to the plan of raising, or pressing it up against the other or stationary one. —

The apparatus consists (when the upper stone is the moving stone) of the following parts, viz. a horizontal lever; a regulating screw; compound levers, and weights; a movable and affixed collar.

The horizontal lever is made of iron or any suitable

ma

May 3, 1832

material and of a size adapted to the purpose intended about the length of the width of the frame of the ~~stele~~ and has an opening formed in its center from one end to a little beyond the point where it rests on the collar ~~base~~ after described, being in the form of two parallel lines, or it may be formed in any convenient manner, so that ~~the~~ the lever may rest on the collar on each side of the spindle. The fulcrum or bearing point of the lever is on its under side and is made in the form of two points, pivots, or spurs one on each arm of the lever, coming to a point or edge at the lower extremity where they rest upon the collar, so that the bearing shall be at the same point, whether the lever be in a horizontal position, or one end elevated, or depressed.

One end of the lever is held in its proper position at the end of the frame and regulated by a screw, wedge or in any convenient manner so as to be moved up or down in order to increase or diminish the effective power of the weights on the compound levers at ~~it~~ other end to be hereafter described. The regulating screw is made of a proper size and strength for the use intended, having a square head resting against the under side of one of the cross rails of the frame through which and the end of the lever it passes, with a nut on its other end by which the lever is regulated. The compound levers and weights are constructed in the following manner. There are two arms of the same dimensions each bent near one end, so that one part shall form an angle with the other of about 40° . These lines are placed in a perpendicular position with the end near which the bend is, placed up, and the convex sides placed towards each other with their fulcrumes fixed at the angles, and attached to a spindle ~~conspindle~~, which may be placed in the center of the ~~conspindle~~

May 3, 1832

compound levers; or to a crossbar attached to said spindle; or to some other permanent object, in such manner that the ends of the levers may move towards & from each other. ... There are three short bars attached at the ends by joints like hinges so that they will bend at the joints; one end of this connexion of bars is attached to the upper end of one of the bent levers, and the other end to the upper end of the other bent lever, in such manner that the middle bar of the three above mentioned is in a horizontal position, and placed across the end of the above described horizontal lever. A ball or weight is attached to the lower end of each bent lever.

The movable and fixed collar or metallic cylindrical collar is fixed permanently to the spindle immediately above this and resting upon it is a moveable collar so fixed, that the spindle may turn freely within it having two small indentations on its upper surface in which rests the points, pivots, or spurs on the underside of the lever first described.

Operation

The mill being put in motion in the usual manner by water, steam, or any convenient power, the operation of the before described apparatus for holding the stones together will be as follows.

When the upper stone is raised or lifted up from the other by any cause whatever, the balls or weights are forced apart and raised, increasing their effective weight or power, and when the upper stone settles towards the other, the balls or weights settle and approach each other by which their effective weight or power is diminished; the apparatus resembling in construction and operation the Governor of a steam engine in the office of a weight.

May 3, 1832

weight of the ball is also increased or diminished by the operation of the regulating screw or weight, pressing the end of the horizontal lever, that which the screw passes when caused to raise it when necessary, the former movement extending the ball or weights, and the latter contracting them; the horizontal lever resting on bearing at or near its centre on the middle collar around the spindle on the points, pivot or spurs on its outer side.

If the mill be constructed with the lower stone to turn and the upper one to remain permanent, the apparatus for forcing the stones together is similar to that above described, with this difference, that the permanent collar on the spindle, which turns the upper is placed above the loose collar; and the horizontal lever rests on a pinion fixed at or near its centre, with one end under the loose collar, and the compound lever fixed at the other end.

Or instead of using the collar on the spindle as before described the horizontal lever may be placed under the oil box in which the lever end of the spindle turns, or it may be fixed in any other convenient manner so that the principle of regulating the lever by the compound lever and weights be retained.

What I claim as my Invention and desire to secure by Letters Patent is the mode of increasing or diminishing the weight of the upper by a self regulating compound power, so that fast and good grinding may be performed with small stones instead of large ones; thereby lessening the expense in constructing mills and so regulating the upper as to prevent any danger of the mill being broken or injured from hard substances getting between the stones and the stone as before described.
